ELECTRICAL POWER SYSTEM

August V. Johansson and Thomas T. Means, Erie, Pa.,
assignors to General Electric Company, a corporation
of New York

Application April 18, 1952, Serial No. 282,972

13 Claims. (Cl. 322—27)

This invention relates to electrical power systems and more particularly to prime mover driven electrical power systems for self-propelled vehicles.

In the design of self-propelled vehicles, such as diesel-electric locomotives, it may be desirable to provide a system of control which will permit the locomotive to be used for very slow speed service during humping operation and also to be used in heavy switching or road service. A locomotive need not provide a large amount of power in order to push a string of freight cars up a hump. However, the control of tractive effort in extremely small increments is desirable. Diesel electric locomotives have previously been designed with control systems providing a plurality, for example, eight increments of tractive effort for starting and operating trains. While such a system is satisfactory for ordinary road and switching service, it prevents close control of the locomotive speed at the very low values found in humping service, i. e. on the order of two to four miles per hour, without almost continuous manipulation of the controller by the engineman.

There are in general two systems for controlling the application of tractive effort in a locomotive; one being a positive system which measures the traction generator line current and varies the excitation supplied to the generator in order to maintain a predetermined current for each throttle notch. The other system of tractive effort control provides predetermined increments of prime mover horsepower by means of throttle manipulation with the traction generator line current being dependent to a great extent upon the speed of the locomotive, i. e. the current being high when the locomotive is at a standstill decreasing rapidly as the locomotive speed increases. The latter system of tractive effort control is not well adapted for humping service since constant manipulation of the throttle is necessary in order to maintain a desired low speed. In order to provide continuously variable or notchless control of excitation for humping service, it is therefore necessary in either system of tractive effort control to employ means for controlling the generator excitation in very small increments to provide a close control of the tractive effort without engine throttle manipulation.

With the system of tractive effort control utilizing engine horsepower control alone, the lack of any method of measuring the actual current produced by the generator in each locomotive unit when a plurality of units are connected for multiple unit operation, makes the system inherently less able to divide load properly between the coupled units. In addition, it is possible to obtain currents greatly in excess of those normally held in road operation in each of the throttle notches and since the humping operation may continue for a considerable period of time, these currents may exceed the short time ratings of the traction motors. These currents are obtained in throttle notches so low that the traction motor blowers, which operate at a speed proportional to the engine speed, cannot deliver sufficient air to cool the motors at the current produced. This condition may further be aggravated on trailing units of a multiple unit locomotive, since, due to the inherent impossibility of controlling motor current at the same value on several coupled units, the current on such trailing units may greatly exceed the current of the leading unit which the operator may have indicated. Thus, the engineman may not be able to avoid over-heated motors when operating in humping service with multiple-coupled units.

2

It is, therefore, seen that a system of locomotive tractive effort control which maintains motor and generator currents at predetermined levels is inherently more suitable for adaptation to humping operation since the danger of excessive motor current in trailing units is eliminated. It is therefore desirable to provide a hump control system for a diesel-electric locomotive which will provide continuously variable or notchless control of tractive effort while preventing application of generator currents

10 in excess of those normally available in each throttle notch. It is also desirable that such a system be incorporated in the tractive effort control system wherein the actual traction motor and generator line current is measured in order to maintain the current at the called for levels. It can be readily seen that such a system should be readily applicable to older locomotives and that the locomotive so equipped must be additionally able to operate properly in road service in multiple unit with locomotives which are not so equipped. Further, 20 it is desirable that only one train wire be utilized in such a system for setting up the circuit from the lead unit of a multiple unit locomotive.

An object of this invention is, therefore, to provide an improved electrical power system for a self-propelled vehicle and more specifically to provide a system for continuously variable or notchless tractive effort control incorporating the desirable features enumerated above.

Further objects and advantages will become apparent and the invention will be better understood by reference 30 to the following description and the accompanying drawing, and features of novelty which characterize this invention will be pointed out with particularity in the claims annexed to and forming a part of this specification.

35 This invention in its broadest aspects provides a generator with means for exciting the same and a resistance bank having a plurality of sections. Supervisory control means are provided arranged selectively to connect the resistance bank sections to the generator exciting means 40 thereby to vary the excitation supplied to the generator. This generator excitation system may include a source of voltage for exciting the separately excited field exciting winding of the generator with means for varying this voltage responsive to the voltage across the resistance bank in order to preselect the desired level of generator line current and means for further varying the exciting voltage responsive to generator line current in order to maintain the generator line current at the preselected value. More specifically, such an arrangement 50 may be a magnetic amplifier having a rectified output connected to vary the voltage applied to the separately excited field of the generator with one direct current winding being energized from the resistance bank in order to establish the desired level of generator line current and another direct current winding being connected across a series field winding, such as the commutating pole winding of the generator so that the magnetic amplifier output and thus the generator excitation is varied in response to the generator line current thereby 55 to maintain the generator line current at the desired level. In order to provide the continuously variable or notchless control of tractive effort, the supervisory control means selectively connects various sections of the resistance bank in circuit with the first magnetic amplifier direct current winding and also controls the speed of the prime mover. Thus, a plurality of predetermined prime mover speeds and an equal number of predetermined generator excitation levels are provided by the controller.

70 In order to provide the continuously variable or notchless control of tractive effort, means are provided continuously to vary the control voltage of the locomotive with the resistance bank being selectively connected either directly to the control voltage source or to the continuously variable means. The continuously variable means may be a potentiometer connected across the source of control voltage with the resistance bank being selectively connected either directly to the source of control voltage or to the movable tap of the potentiometer. It is thus readily seen that the voltage applied to the resistance bank may be continuously varied from

the maximum value of the control voltage down to a lower level. Thus, in each notch of the main controller, the tractive effort may be reduced from the maximum level of that particular notch down to a much lower value by manipulation of the movable tap of the potentiometer. In order to provide for multiple unit operation, a train wire circuit is provided in each locomotive unit adapted to be connected to a similar train wire circuit in each other vehicle. The movable tap of the notchless tractive effort potentiometer is connected to the train wire connected either directly to the source of control voltage or to the train wire. Thus, manipulation of the notchless tractive effort potentiometer in lead locomotive unit will vary the voltage on the train wire in each unit thus applying the same voltage to the resistance bank in each unit and therefore providing the same generator excitation in each unit.

The single figure of the drawing schematically illustrates the improved electrical power system of this invention.

Referring now to the drawing, there is shown a traction generator 1, having a separately excited field exciting winding 2 and a series field exciting winding 3, for example a commutating pole winding. The generator 1 is adapted to be connected to a plurality of traction motors, one being shown schematically at 4. It will be readily understood that suitable switching arrangements would be provided to connect the traction motors 4 for either series or parallel operation, however, since these arrangements form no part of this invention, they will not be further described. The separately excited field of the generator 1 is connected for exciting winding 2 of the generator 1 is connected for energization from an exciter machine 5 having a control field exciting winding 6. The exciter machine 5 may be an armature reaction excited machine of the type referred to as an amplidyne. Both the generator 1 and the exciter machine 5 are driven by a suitable prime mover 7, such as a diesel engine.

In order to energize the control field winding 6 of the amplidyne exciter 5, the control field winding is connected across a source of control voltage 8 and 9 and has a resistor 10 arranged in series therewith. In order to vary the voltage appearing across the amplidyne control field winding 6 and thus vary the excitation supplied to the generator separately excited field winding 2, a magnetic amplifier 11 is provided having a pair of three-legged core reactors 12 and 13. The outer legs of the reactors 12 and 13 are provided with windings 14, 15, 16 and 17 which are serially connected for energization from a suitable source of alternating current (not shown) by lines 18 and 19. A bridge rectifier 20 has its input connected across line 19 and the connection between alternating current windings 15 and 16 as at 21. The output of the bridge rectifier 20 is connected across a resistor 10 in series with the amplidyne exciter control field winding 6. In order to control magnetic amplifier 11, a pair of direct current windings 22 and 23 are respectively arranged on the center legs of the reactors 12 and 13 and serially connected across the source of control voltage 8 and 9. Another direct current winding 24 is arranged on the center leg of reactor 12 and connected across series field exciting winding 3 of generator 1. Windings 22 and 24 on reactor 12 are arranged to be additive.

In order to control the input to the magnetic amplifier 20 and ultimately the excitation applied to the separately excited field exciting winding 2 of generator 1, a resistance bank 25 is provided having taps 26 through 32 inclusive. The resistance bank 25 has its end 26 connected to positive control line 8 through normally closed contact 34 of hump control relay 35 with fixed resistance contact 36 being arranged in the circuit. The taps 26 to 32 of resistance bank 25 are respectively connected to cam actuated contacts 37 through 43 of drum controller 45, the contacts 37 to 43 being also connected to common line 46. Common line 46 is in turn connected to the negative control line 9 through contact 44 of drum controller 45. The direct current winding 23 of reactor 13 is connected across the resistance bank 25 by means of line 47 connecting the end 26 of resistance bank 25 and the connection 48 between direct current windings 22 and 23, and common line 46 to which reactor coil 23 is connected at 49. The drum controller 45 has 23 eight positions and an off position, the contacts 37 to

43 being successively closed in the first seven positions to progressively short sections of the resistance bank 25 and none of the contacts 37 to 43 being closed in the eighth position. The contact 44 connecting common line 46 to the negative control line 9 is closed in each of the eight positions of controller 45 and open in the off position.

Assuming for the moment that voltages appearing across direct current reactor windings 22 and 23 are equal so that equal saturation is provided in the cores 12 and 13, it will be seen that the voltage appearing across point 21 and line 19 will be equal to the voltage appearing across point 21 and line 18 and therefore half of the voltage appearing across lines 18 and 19 will be impressed upon the bridge rectifier 20 and the rectified output applied to the resistor 10. The voltage impressed by the rectifier 20 on the resistor 10 is arranged to buck the voltage across control lines 8 and 9 and thus the ultimate voltage appearing across amplidyne exciter control field winding 6 will be the difference between the control voltage appearing across lines 8 and 9 and the bucking voltage impressed upon the resistor 10 by the bridge rectifier 20. Assuming now that generator 1 is connected to traction motors 4 so that load current flows through the series field exciting winding 3, a voltage will appear across the direct current winding 24. This will increase the unidirectional flux flowing in the center leg of reactor 12 and through the side legs on which the windings 14 and 15 are wound and the resultant increase in saturation of reactor 12 and in the reactance of windings 14 and 15 will therefore decrease the voltage appearing across point 21 and line 18. The voltage appearing across point 21 and line 19 will therefore increase by a corresponding amount thus increasing the voltage impressed upon the bridge rectifier 20 and the bucking voltage applied to the resistor 10. With an increase in the bucking voltage, the voltage across the amplidyne exciter control field winding 6 will be decreased by a corresponding amount, thus decreasing the excitation applied to the generator separately excited field winding 2 and decreasing the line current supplied by generator 1. Correspondingly, a decrease in the line current flowing in the series field winding 3 of generator 1 will decrease the voltage appearing across direct current winding 24 of reactor 12 thus decreasing the unidirectional flux producing a corresponding decrease in reactance of windings 14 and 15. This will increase the voltage appearing across point 21 and line 18 with a corresponding decrease in the voltage across point 21 and line 19. This in turn produces a decrease in the voltage applied to the bridge rectifier 20 and the voltage impressed upon resistor 10 so that increased voltages are applied to amplidyne exciter control field winding 6 and to generator separately excited field winding 2. Thus, an increase in the generator line current will be produced. It is thus seen that with the voltages appearing across direct current windings 22 and 23 remaining constant, an increase in line current flowing in the field winding 3 will produce a corresponding decrease in the excitation supplied to separately excited field winding 2 to restore the line current to its original value and correspondingly a decrease in the line current flowing in the field winding 3 will produce a corresponding increase in the excitation applied to the separately excited field winding 2 to again restore the current to its original level. Thus, the line current of the generator 1 is measured in order to vary the excitation supplied to the generator 1 to maintain the line current at the desired level.

It will now be readily seen that varying the amount of resistance across direct current winding 23 by operating controller 45 to progressively close contacts 37 to 43 and thus progressively short the sections of the resistance bank, will increase the voltage applied to the winding 23 and decrease the voltage applied to the winding 22. Thus, assuming that controller 45 is in the first position with contact 37 closed, the entire resistance bank 25 and thus the winding 23 will be shorted and the entire voltage across control lines 8 and 9 will appear across winding 22. With this condition, the reactor 12 will be highly saturated so that a low voltage appears across point 21 and line 18 with variations in the voltage applied to winding 24 varying the voltage about that level. Thus, the voltage across point 21 and line 19 and thus across rectifier 20 is correspondingly high with variations of the voltage applied to winding 24 responsive to generator line

current producing variations in the rectifier output about that level. It is therefore seen that with resistance bank 25 completely shorted, a high level of bucking voltage is applied to resistor 130 by rectifier 20 and thus a relatively low level of excitation is supplied to amplidyne exciter control field winding 6 and generator field winding 2. However, as contacts 37 to 43 of controller 45 are progressively closed as the controller is moved from position 1 to position 7, it is seen that progressively larger sections of resistance bank 25 are connected across winding 23 thus increasing the current flow in that winding and decreasing the current flow in winding 22. With all of the contacts 37 to 43 open in the eighth position of controller 45, none of the resistance bank 25 is connected across direct current winding 23 so that the highest voltage appears thereacross reducing the voltage applied to rectifier 20 and thus to the bucking resistor 10 to the lowest level. The voltage therefore applied to amplidyne exciter control field winding 6 is at its highest level to call for the highest current output of generator 1. It is thus seen that the generator current is varied in a plurality of steps, shown here as being 8, by manipulation of drum controller 45 and that in each position of the controller 45 calling for a predetermined level of generator line current the magnetic amplifier 11 energized rendering 3 will modify the bucking voltage appearing across resistor 10 to maintain the current at the desired level. It will be readily understood that in multiple unit operation, the system thus far described will be provided in each cab with the controller shown schematically at 45 in each trailing cab being operated by the engineman in the leading cab. This system of multiple unit control does not form a part of this invention and will not be more fully described.

It will be readily seen that with the arrangement hereinbefore described, tractive effort of the locomotive can only be varied in the eight steps or notches provided by controller 45. In order to provide a supplemental notchless control of tractive effort, continuously variable potentiometer 51 is connected across common line 46 and a positive control line 8 with hump control switch 52 being arranged in series therewith. The movable tap 53 of hump control potentiometer 51 and switch 52 are both operated by hump controller 54 with tap 53 being connected to train wire 55 through contact 56 of reverser controller 57 and line 58. It will be readily understood that train wire 55 is adapted to be connected to similar train wires in other locomotive units and that the control arrangement hereinbefore described will be found in each unit. Reverser controller 57 has forward, off, and reverse positions with contact 56 being closed in the forward and reverse positions only. The desirability of inaftter described. The movable tap 53 of hump control potentiometer 51 and line 58 are also connected to operating coil 59 of hump control relay 35 through its normally closed contact 60, the other side of the operating coil 59 being connected to common line 46. The operating coil 59 of hump control relay 35 is also arranged to be connected directly to positive control line 8 through its normally open contact 61. It will thus be seen that with the movable tap 53 of hump control potentiometer 51 in the position shown in the drawing so that switch 52 is closed, with the reverser 57 in either the forward or the reverse position so that the contact 56 is closed, operating coil 59 of hump control relay 35 will be energized from line 8 and will pick up thus opening its normally closed contacts 60 and sealing itself in directly to line 8 through its contact 61. Picking up of hump control relay 35 opens its normally closed contact 34 which connected resistance bank 25 and resistance 36 to positive control line 8 and closes normally open contact 62 connecting resistance bank 25 and fixed resistor 36 to the train wire 55. It is now seen that resistance bank 25 and resistance 36 are energized from positive control line 8 through switch 52, potentiometer 51, contact 56, line 58, train wire 55, and contact 62. It is thus seen that with the movable tap 53 of hump control potentiometer 51 at the extreme end 63 as shown in the drawing, the voltage applied to the resistance bank 25 and resistance 36 will be the same as that applied when the resistance bank and fixed resistance are connected directly to the positive control line 8 through contact 34 of hump control relay 35. However, it will be seen that by operating hump controller 54, the movable tap 53 of hump control potentiometer 51 may be

5 moved toward its other extremity 64 to continuously reduce the voltage applied to the circuit including the fixed resistor 36 and the resistance bank 25. It is thus seen that as the controller 54 is advanced the voltage across that portion of resistance bank 25 selected by controller 45 is reduced thus reducing the voltage on the reactor winding 23. This in turn increases the input to bridge rectifier 20 thus increasing the bucking voltage applied to the resistor 10 and decreasing the voltage on the amplidyne exciter control field winding 6. Thus, as the controller 54 is advanced with the controller 45 in any position, the excitation supplied to the generator separately excited field winding 2 is smoothly reduced thereby to reduce the generator line current called for.

15 Since the train wire 55 is connected to similar wires in other locomotive cabs and since the same control arrangement is found in each cab, it will be apparent that by manipulating controller 54 in the lead cab, the voltage on the train wire is varied in each cab thus producing the same variation in the voltage appearing across resistance bank 25 and resistance 36 and in the excitation supplied to the generator in each cab. The controller 20 57 is connected in the circuit since it might otherwise be possible for someone to manipulate potentiometer 51 in one of the trailing cabs and thus adversely affect the tractive effort called for by the engineman. To eliminate this possibility, it will be noted that in each of the trailing cabs, the resistance bank 25 and resistance 36 are supplied directly from train wire 55 through contact 62.

25 30 Since the handle for controller 57 will only be found in the lead cab, and thus the contacts 56 in the trailing units will not be closed, it will be impossible for anyone to operate the potentiometer 51 in any of the trailing cabs to change the setting called for by the engineman.

35 35 Hump control relay has a normally open contact 65 which shorts switch 52 thus permitting the controller 54 to be returned to the off or full field position 63 without deenergizing potentiometer 51.

It will be seen that this system provides a gradually increasing range to the total movement of the hump control potentiometer 51 as the controller 45 is advanced toward the higher notches. For example, in notch 1 of controller 45, the minimum engine speed is called for by virtue of the connection of the controller 45 to the engine shown schematically at 66 and also minimum generator excitation is called for since the resistor bank 25 is completely short-circuited. In this notch, no control is provided by hump control potentiometer 51 since the level of excitation supplied to the generator 1 is entirely established by reactor winding 22 which in the first notch of controller 45 is directly energized across lines 8 and 9. In notch 2, manipulation of hump controller 54 to vary the setting of hump control potentiometer 51 will provide something less than notch 2 tractive effort and in each successively higher notch of controller 45, manipulation of the hump control potentiometer 51 will continuously vary the tractive effort downward from that called for by the particular controller notch to a much lower level. It will be readily seen that for each notch of controller 45, the minimum tractive effort will be provided with hump control potentiometer 51 in its extremity 64 since in this position resistor 36 is effectively connected in parallel with resistance bank 25 with this network and parallel connected reactor winding 23 being fed from line 8 through reactor winding 22. It will be seen that once the hump control switch 52 is closed, the hump control relay 35 will pick up sealing itself into the positive control line 8 through its contacts 61. However, it will be seen that when the controller 45 is moved to the off or idling position, contact 44 connecting common line 46 to negative control line 9 will be opened, thus opening the circuit of operating coil 59 of hump control relay 35 to drop out the relay. Capacitor 67 provides a temporary path for the pickup current of relay 35 during the instant when contact 60 is open and before contact 61 has closed.

To summarize, it will now be readily seen that the excitation supplied to generator 1 and thus the line current of the generator is set at a plurality of predetermined values by means of the controller 45 which simultaneously sets the speed of the diesel 7 at a plurality of predetermined values. The line current of the generator 1 is measured by means of the reactor coil 24 and the magnetic amplifier 11 functions to maintain the line current at the desired predetermined value, the amount of

the resistance bank 25 connected in parallel with reactor winding 23 determining the generator line current level. In order to provide the notchless tractive effort humping control, the train wire 55 and all similar train wires in other cabs, are energized to pick up the hump control relay 35, energization of train wire 55 in other locomotive cabs also picking up the hump control relays in those cabs through lines 58. Picking up of the hump control relays 35 connects resistance bank 25 and resistor 36 to the train wire 55 rather than directly to the positive control line 8, the train wire 55 being in turn energized from the movable element 53 of hump control potentiometer 51. It is thus seen that this invention requires the use of only one train wire for initially setting up the notchless hump control system and for subsequent modulation of the control in both the leading cab and trailing multiple unit cabs. Furthermore, this system provides notchless tractive effort control without danger of over-load of the traction motors of any one of a group of multiple unit connected cabs since each of the locomotive units is provided with the generator current limiting arrangement here shown. In addition, this arrangement can be readily added to existing locomotives having an eight notch throttle and a current limit excitation system. It is, therefore, readily apparent that this invention provides an improved electrical power system for a self-propelled vehicle characterized by its simplicity, ease of installation, and superior tractive effort control.

While we have shown and described a particular embodiment of this invention, further modifications and improvements will occur to those skilled in the art. We desire it to be understood, therefore, that this invention is not limited to the form shown and we intend in the appended claims to cover all modifications which do not depart from the spirit and scope of this invention.

What we claim as new and desire to secure by Letters Patent of the United States is:

1. An electric power system for a self-propelled vehicle comprising a generator having exciting means, a source of control voltage, a resistance bank having a plurality of sections, supervisory control means having a plurality of positions arranged selectively to connect said resistance sections in circuit with said exciting means thereby to vary the excitation supplied to said generator in a plurality of steps, a continuously variable potentiometer connected across said source of control power and having a movable tap, a train wire circuit adapted to be connected to similar circuits in other vehicles, said movable tap of said potentiometer being connected to said train wire circuit, switch means arranged selectively to connect said resistance bank directly to said source of control voltage or to said train wire circuit thereby smoothly to vary the voltage applied to said resistance bank whereby the excitation supplied to said generator is smoothly varied, and other supervisory control means arranged to operate said potentiometer tap.

2. An electrical power system for a self-propelled vehicle comprising a generator having exciting means, a source of control voltage, a resistance bank having a plurality of sections, supervisory control means having a plurality of positions, arranged selectively to connect said resistance sections in circuit with said exciting means thereby to vary the excitation supplied to said generator in a plurality of steps, a train wire adapted to be connected to similar circuits in other vehicles, a continuously variable potentiometer connected across said source of control voltage and having a movable tap connected to said train wire circuit, a relay having an operating coil with one side thereof connected to one side of said source of control voltage and having its other side connected to said train wire circuit, said relay having a contact connecting said resistance bank directly to said control voltage when said relay is deenergized and another contact connecting said resistance bank to said train wire circuit when said relay is energized so that operation of said potentiometer smoothly varies the voltage applied to said resistance bank thereby smoothly to vary the excitation supplied to said generator, and other supervisory control means arranged to operate said potentiometer tap.

3. An electrical power system for a self-propelled vehicle comprising a generator having an exciting means, a source of control voltage, a resistance bank having a plurality of sections, supervisory control means having a plurality of positions arranged selectively to connect said

resistance sections in circuit with said exciting means thereby to vary the excitation supplied to said generator in a plurality of steps, a train wire circuit adapted to be connected to similar circuits and other vehicles, a continuously variable potentiometer connected across said source of control voltage and having a movable tap connected to said train wire circuit, a relay having an operating coil with one side thereof connected to one side of said source of control voltage, said relay having a contact connecting the other side of said operating coil to said train wire circuit when said relay is deenergized and another contact connecting said other side of said operating coil to said other side of said source of control voltage when said relay is energized, said relay having a contact connecting said resistance bank directly to said source of control voltage when said relay is deenergized and another contact connecting said resistance bank to said train wire circuit when said relay is energized whereby said potentiometer smoothly varies the voltage applied to said resistance bank thereby smoothly to vary the excitation supplied to said generator, and other supervisory control means arranged to operate said potentiometer tap.

4. An electrical power system for a self-propelled vehicle comprising a generator adapted to be connected to a load and having a separately excited field exciting winding, a source of voltage for energizing said separately excited field winding, a magnetic amplifier having a rectified output connected to vary said voltage thereby to vary the excitation supplied to said separately excited field winding, said magnetic amplifier having a direct current winding electrically connected for energization responsive to the load current of said generator whereby the excitation supplied to said separately excited field winding is varied thereby to maintain said generator load current at a predetermined value, said magnetic amplifier having another direct current winding, a resistance bank having a plurality of sections, supervisory control means having a plurality of positions arranged selectively to connect said resistance sections to said other magnetic amplifier direct current winding thereby further to vary the energization supplied to said separately excited field winding whereby the value of said generator load current is established, a source of control voltage, means arranged smoothly to vary said source of control voltage, 50 switch means arranged selectively to connect said resistance bank directly to said source of control voltage or to said continuously varying means thereby smoothly to vary the voltage applied to said resistance bank whereby the excitation supplied to said generator is smoothly varied, and other supervisory control means arranged to operate said continuously variable means.

5. An electrical power system for a self-propelled vehicle comprising a generator adapted to be connected to a load and having a separately excited field exciting winding, a source of voltage for energizing said separately excited field winding, a magnetic amplifier having a rectified output connected to vary said voltage thereby to vary the excitation supplied to said separately excited field windings, said magnetic amplifier having a direct current winding electrically connected for energization responsive to the load current of said generator whereby the excitation supplied to said separately excited field winding is varied thereby to maintain said generator load current at a predetermined value, said magnetic amplifier having another direct current winding, a resistance bank having a plurality of sections, supervisory control means having a plurality of positions arranged selectively to connect said resistance sections to said other magnetic amplifier direct current winding thereby further to vary the energization supplied to said separately excited field winding whereby the value of said generator load current is established, a source of control voltage, a continuously variable potentiometer connected across said source of control voltage and having a movable tap, switch means arranged selectively to connect said resistance bank directly to said source of control voltage or to said potentiometer tap thereby smoothly to vary the voltage applied to said resistance bank whereby the excitation supplied to said generator is smoothly varied, and other supervisory control means arranged to operate said potentiometer tap.

6. An electrical power system for a self-propelled vehicle comprising a generator adapted to be connected to a load and having a separately excited field exciting winding, a source of voltage for energizing said separately excited field winding, a magnetic amplifier having a rectified output connected to vary said voltage thereby

to vary the excitation supplied to said separately excited field winding, said magnetic amplifier having a direct current winding electrically connected for energization responsive to the load current of said generator whereby the excitation supplied to said separately excited field winding is varied thereby to maintain said generator load current at a predetermined value, said magnetic amplifier having another direct current winding, a resistance bank having a plurality of sections, supervisory control means having a plurality of positions arranged selectively to connect said resistance sections to said other magnetic amplifier direct current winding thereby further to vary the energization supplied to said separately excited field winding whereby the value of said generator load current is established, a source of control power, a continuously variable potentiometer connected across said source of control power and having a movable tap, a train wire circuit adapted to be connected to similar circuits in other vehicles, said movable tap of said continuously variable potentiometer being connected to said train wire circuit, switch means arranged selectively to connect said resistance bank directly to said source of control voltage or to said train wire circuit thereby smoothly to vary the voltage applied to said resistance bank whereby the excitation supplied to said generator is smoothly varied, and other supervisory control means arranged to operate said potentiometer tap.

7. An electrical power system for a self-propelled vehicle comprising a generator adapted to be connected to a load and having a separately excited field exciting winding, a source of voltage for energizing said separately excited field winding, a magnetic amplifier having a rectified output connected to vary said voltage thereby to vary the excitation supplied to said separately excited field winding, said magnetic amplifier having a direct current winding electrically connected for energization responsive to the load current of said generator whereby the excitation supplied to said separately excited field winding is varied thereby to maintain said generator load current at a predetermined value, said magnetic amplifier having another direct current winding, a resistance bank having a plurality of sections, supervisory control means having a plurality of positions arranged selectively to connect said resistance sections to said other magnetic amplifier direct current winding thereby further to vary the energization supplied to said separately excited field winding whereby the value of said generator load current is established, a source of control power, a train wire circuit adapted to be connected to similar circuits in other vehicles, a continuously variable potentiometer connected across said source of control voltage and having movable tap connected to said train wire circuit, a relay having an operating coil with one side thereof connected to one side of said source of control voltage and the other side thereof connected to said train wire circuit, said relay having a contact connecting said resistance bank directly to said source of control voltage when said relay is deenergized and another contact connecting said resistance bank to said train wire circuit when said relay is energized whereby said potentiometer smoothly varies the voltage applied to said resistance bank thereby smoothly to vary the excitation supplied to said generator, and other supervisory control means arranged to operate said potentiometer tap.

8. An electrical power system for a self-propelled vehicle comprising a generator adapted to be connected to a load and having a separately excited field exciting winding, a source of voltage for energizing said separately excited field winding, means for varying said source of voltage responsive to the load current of said generator whereby said generator load current is maintained at a predetermined value, means for further varying said source of voltage responsive to the load current of said generator, a resistance bank having a plurality of sections, supervisory control means having a plurality of positions arranged selectively to connect said resistance sections to said last-named voltage varying means thereby to establish the value of said generator load current, a source of control power, means arranged continuously to vary said source of control voltage, switch means arranged selectively to connect said resistance bank directly to said source of control voltage or to said continuously varying means thereby smoothly to vary voltage applied to said resistance bank whereby the excitation supplied to said generator is smoothly varied, and other supervisory control means arranged to vary said continuously varying means.

9. An electrical power system for a self-propelled vehicle comprising a generator adapted to be connected to a load and having a separately excited field exciting winding, a source of voltage for energizing said separately excited field winding, means for varying said source of voltage responsive to the load current of said generator whereby said generator load current is maintained at a predetermined value, means for further varying said source of voltage, a resistance bank having a plurality of positions arranged selectively to connect said resistance sections to said last-named voltage varying means thereby to establish the value of said generator load current, a source of control power, a continuously variable potentiometer connected across said source of control voltage and having a movable tap, switch means arranged selectively to connect said resistance bank directly to said source of control voltage or to said potentiometer tap thereby smoothly to vary the voltage applied to said resistance bank whereby the excitation supplied to said generator is smoothly varied, and other supervisory control means arranged to operate said potentiometer tap.

10. An electrical power system for a self-propelled vehicle comprising a generator adapted to be connected to a load and having a separately excited field exciting winding, a source of voltage for energizing said separately excited field winding, means for varying said source of voltage responsive to the load current of said generator whereby said generator load current is maintained at a predetermined value, means for further varying said voltage, a resistance bank having a plurality of sections, supervisory control means having a plurality of positions arranged selectively to connect said resistance sections to said last-named voltage varying means thereby to establish the value of said generator load current, a source of control power, a train wire circuit adapted to be connected to similar circuits in other vehicles, a continuously variable potentiometer connected across said source of control voltage and having a movable tap connected to said train wire circuit, switch means arranged selectively to connect said resistance bank directly to said source of control voltage or to said train wire circuit whereby said potentiometer smoothly varies the voltage applied to said resistance bank thereby smoothly to vary the excitation supplied to said generator, and other supervisory control means arranged to operate said potentiometer tap.

11. An electrical power system for a self-propelled vehicle comprising a generator adapted to be connected to a load and having a separately excited field exciting winding, a source of voltage for energizing said separately excited field winding, means for varying said source of voltage responsive to the load current of said generator whereby said generator load currents maintained at a predetermined value, means for further varying said voltage, a resistance bank having a plurality of sections, supervisory control means having a plurality of positions arranged selectively to connect said resistance sections to said last-named voltage varying means thereby to establish the value of said generator load current, a source of control power, a train wire circuit adapted to be connected to similar circuits in other vehicles, a continuously variable potentiometer connected across said source of control voltage and having a movable tap connected to said train wire circuit, a relay having an operating coil with one side thereof connected to one side of said source of control voltage and the other side thereof connected to said train wire circuit, said relay having a contact connecting said resistance bank directly to said source of control voltage when said relay is deenergized and another contact connecting said resistance bank to said train wire circuit when said relay is energized whereby said potentiometer smoothly varies the voltage applied to said resistance bank thereby smoothly to vary the excitation supplied to said generator, and other supervisory control means arranged to operate said potentiometer tap.

12. An electrical power system for a self-propelled vehicle comprising a generator adapted to be electrically connected to a load and having a separately excited field exciting winding, a source of voltage connected to energize said separately excited field winding, means including a magnetic amplifier having a rectified output connected to vary said voltage thereby to vary the excitation supplied to said separately excited field winding, said magnetic amplifier having a pair of direct cur-

rent windings serially connected across source of control voltage, a resistance circuit including a resistance bank having a plurality of sections and another resistance bank connected in series therewith, a train wire circuit adapted to be connected to similar circuits in other vehicles, supervisory control means having a plurality of positions arranged selectively to connect said resistance bank sections to one of said magnetic amplifier direct current windings thereby to vary the voltage supplied to said one magnetic amplifier direct current winding whereby the excitation supplied to said separately excited field winding is varied to determine the load current of said generator, said magnetic amplifier having another direct current winding energized responsive to the load current of said generator whereby said load current is maintained at the value determined by said supervisory control means, a continuously variable potentiometer connected across said source of control voltage and having a movable tap connected to said train wire circuit, switch means arranged selectively to connect said resistance circuit directly to said source of control voltage or to said train wire circuit whereby said potentiometer smoothly varies the voltage applied to said first-named circuit thereby smoothly to vary the excitation supplied to said generator, and other supervisory control means arranged to operate said potentiometer tap.

13. An electrical power system for a self-propelled vehicle comprising a generator adapted to be electrically connected to a traction motor and having a separately excited field exciting winding and a series field exciting winding, a source of voltage connected to energize said separately excited field winding, means including a magnetic amplifier having rectified output connected to vary said voltage thereby to vary the excitation supplied to said separately excited field winding, said magnetic amplifier having a pair of direct current windings serially connected across said source of control voltage, a resistance circuit including a resistance bank having a plu-

rality of sections and another resistance connected in series therewith, a train wire circuit adapted to be connected to similar circuits in other vehicles, supervisory control means having a plurality of positions arranged selectively to connect said resistance bank sections to one of said magnetic amplifier direct current windings thereby to vary the voltage supplied to said one magnetic amplifier direct current winding whereby the excitation supplied to said separately excited field winding is varied to determine the load current of said generator, said magnetic amplifier having another direct current winding connected across said series field winding whereby said first-mentioned voltage is varied responsive to the load current of said generator thereby to maintain said load current at the value determined by said supervisory control means, a continuously variable potentiometer connected across said source of control voltage and having a movable tap connected to said train wire circuit, a relay having an operating coil with one side thereof connected to said source of control voltage and the other side to said train wire circuit, said relay having a contact connecting said resistance circuit directly to said source of control voltage when said relay is deenergized and another contact connecting said resistance circuit to said train wire circuit when said relay is energized whereby said potentiometer smoothly varies the voltage applied to said resistance circuit thereby smoothly to vary the excitation supplied to said generator, and other supervisory control means arranged to operate said potentiometer tap.
